UNITED STATES PATENT OFFICE.

ALBERT H. TAYLOR AND LEO C. YOUNG, OF WASHINGTON, DISTRICT OF COLUMBIA,
ASSIGNORS TO WIRED RADIO, INC., OF NEW YORK, N. Y., A CORPORATION OF DELA-
WARE.

RADIO SIGNALING APPARATUS.

Application filed January 7, 1925. Serial No. 1,055.

These improvements relate particularly to radio signaling apparatus and more particularly to improvements in radiating systems thereof.

5 The particular object of our invention is to provide an efficient radiating system for radio signaling apparatus where the radiating system leads are long and must be encased in insulators or suspended in metal 10 trunks, or suspended by insulating substances in the near vicinity of grounded metal.

Another object of our invention is to reduce the radiating losses when the leads to 15 the radiating system of radio signaling apparatus are encased or surrounded by grounded metal.

A further object of our invention is to provide a radiating system whose free 20 period of oscillation of the antenna proper is uninfluenced by the capacity effect of the leads between the transmitter and the antenna proper.

A still further object of our invention is 25 to improve the purity of the wave form of radiated oscillations when the leads to the radiating system are encased in metal or surrounded in the near vicinity by metal.

With the above and other objects in view 30 the invention consists in the construction, combination and arrangement of parts, as will be hereinafter more fully described.

Reference is to be had to the accompanying drawings forming part of this specification, 35 in which the like reference characters indicate corresponding parts throughout the several views, and in which

Figure 1 discloses the general embodiment of the invention in which the various 40 circuits are coupled inductively.

Figure 2 represents a modification in which the coupling between the circuits is by means of auto-transformers.

Figure 3 represents a modification in 45 which a second intermediate circuit is disconnected, and

Figure 4 represents a modification using a combination of auto-transformers and inductively coupled transformers with inserted indicating means.

Referring more particularly to the drawings, and especially to Figure 1, 1 represents the plate electrode of a power tube arranged in an oscillation circuit which has been only

partially illustrated; 2 represents the plate feed circuit; 3 represents a choke coil in the plate feed circuit; 4 represents a stopping condenser, and 5 represents the inductance tuning coil. This circuit is the usual power tube arrangement. The inductance tuning coil 6, tuning condenser 7, antenna lead 14, and metal trunk 8, form a link circuit between the transmitter and the radiating system proper. The antenna or radiating system proper comprises antenna 12, inductance coil 11, tuning capacity 10, and ground 13.

By inserting this intermediate circuit between the transmitter and the antenna proper, the tuning of the antenna, especially to short waves, is very much simplified, for, if the antenna leads are long and are suspended in hollow metal trunks, such as when the transmitter is on one of the lower floors of a building with the antenna supported above the roof, the greater share of the capacity of the radiating system is in the lead. The ratio of the capacity of the leads to the capacity of the antenna proper is sometimes as high as four to one, which means that four fifths of the current output of the transmitter is expended in charging up the capacity of the leads to ground. While the actual power losses in watts may not be very great, still it represents an additional load on the tube which is undesirable and at the same time the added difficulties of tuning the radio system with such a peculiar antenna are very difficult for the active or effective portion of the antenna is very limited. For very short wave lengths the free period of the antenna is so uncomfortably close to the frequency of the transmitter and the active portion of the radiating system must be made so small that radiation will be very inefficient and the radiated signals will be very weak. By means of this invention, however, the design of the antenna proper may be such that its actual period is practically equal to the period of the radiated frequency, allowance being made for inductance for coupling only.

The accompanying drawings show four methods of coupling the intermediate circuit or circuits between the power tubes and the antenna proper. However, this invention is not limited to a power tube transmitter or to the particular forms of coupling the link circuit as shown.

In Figure 1 the tuning of the plate circuit is accomplished by varying of inductance in coil 5. The intermediate circuit is coupled to the plate circuit by coils 5 and 6, which coils function as a transformer. The tuning of the intermediate circuit is accomplished by varying condenser 7 and coils 6 and 9. The radiating antenna proper is coupled to the intermediate circuit by coils 9 and 10 which function as a transformer. The tuning of the radiating circuit is accomplished by varying capacity 10 and inductance 11.

Figure 2 shows a modification in which the coupling of the three circuits is direct rather than inductive and the tuning of the antenna circuit is accomplished by varying the inductance only. Coils 15 and 16 perform the function of tuning coils and may be considered auto transformers. Condenser 7 is included at the lower end of the antenna trunk lead 14 and is highly essential in the operation of the circuit, but it does not sharply tune the trunk line circuit. The variable condenser 7 in this case acts more as a coupling condenser, feeding energy over to the coupling inductance 16.

Figure 3 shows a modified circuit arrangement in which a second intermediate circuit is provided, consisting of inductance coils 17 and 18 and condenser 19. This circuit is added between the transmitter and the link circuit and gives a sharp tuning arrangement and has a beneficial effect upon the purity of the emitted wave.

Figure 4 shows a modification in which the auto-transformer and tuning arrangement 15 is the same as in Figure 2. Condenser 10 may remain fixed over a wide range of wave lengths and tuning may be accomplished by a variometer 20 operated by any remote control system such as a motor controlled through shielded leads from the transmitting room, the motor being properly geared to the shaft of the variometer. A thermo couple 21 is inserted at the base of the antenna proper and may be connected through shielded leads to an indicating ammeter in the transmitting room.

It will be understood that the above description and accompanying drawings comprehend only the general and preferred embodiment of our invention and that various minor changes in details of construction, proportion and arrangement of parts may be made within the scope of the appended claims without sacrificing any of the advantages of our invention.

What we claim is:

1. In a radio transmission system a high frequency oscillation circuit, a high frequency radiation system located at a distance from said high frequency oscillation circuit, an auto-transformer inductance system connected in said oscillation circuit and

in said radiation system, a lead, including a series connected adjustable capacity element interconnecting said auto-transformer inductance systems, and a metallic trunk surrounding said lead and connected with the midpoints of said auto-transformer inductance systems and to ground for suppressing the radiation of energy intermediate said oscillation circuit and said radiation system.

2. In a radio transmission system a high frequency oscillation circuit, a high frequency radiation system located at a distance from said high frequency oscillation circuit, an auto-transformer inductance system connected in said oscillation circuit and in said radiation system, each of said transformer systems including a pair of windings connected at adjacent ends, a lead, including a series connected adjustable capacity disposed between one winding of each of said transformer systems, and a metallic trunk surrounding said lead and connected with the adjacent ends of each of said pair of windings and to ground, for permitting the transfer of high frequency energy from said high frequency oscillation circuit to said radiation system, while suppressing radiation intermediate said oscillation circuit and said radiation system.

3. In a radio transmission system a high frequency oscillation circuit, a high frequency radiation system located at a distance from said high frequency oscillation circuit, an auto-transformer inductance system connected in said oscillation circuit and in said radiation system, each of said transformer systems including a pair of windings connected at adjacent ends, a tuned circuit connected with one winding of one of said transformer systems, an extended conductor connected with one winding of the other of said transformer systems and including a tuned circuit in series therewith and in coupled relationship with said first mentioned tuned circuit, a metallic trunk surrounding said extended conductor and connected with the adjacent ends of each of said pair of windings, and connections between said second mentioned tuned circuit, said metallic trunk and ground, whereby the transfer of high frequency energy from said high frequency oscillation circuit to said radiation system may be effected while suppressing radiation intermediate said oscillation circuit and said radiation system.

4. In a radio transmission system a high frequency oscillation circuit, a high frequency radiation system located at a distance from said high frequency oscillation circuit, an auto-transformer inductance system connected in said oscillation circuit and in said radiation system, each of said transformer systems including a pair of windings connected at adjacent ends, a tuned circuit connected with one winding of the auto-trans-

former inductance system in said high frequency oscillation circuit, an extended conductor connected with one winding of said auto-transformer inductance system in said 5 radiation system, said conductor including a tuned circuit in series therewith, and in coupled relationship with said first mentioned tuned circuit, a metallic trunk surrounding said extended conductor and connected with 10 the adjacent ends of each of said pair of windings, and connections between said second mentioned tuned circuit, said metallic trunk and ground, whereby the transfer of high frequency energy from said high frequency oscillation circuit to said radiation 15 system may be effected while suppressing radiation intermediate said oscillation circuit and said radiation system.
